2 Claims. (Cl. 15—160)

This invention relates generally to improvements in 10 brushes, and more particularly it pertains to a novel arrangement of the bristle tufts thereon. This patent application is a division of U.S. Letters Patent 2,974,338 of David C. Roth and Karl H. Florenz, issued March 14, 1961, for "Brushes."

One object of this invention is to provide a unique brush, the bristle tufts of which tend to alternately gouge or lift the material being brushed and, at the same time, to sweep the material being brushed.

Another object of this invention is to provide a brush, the bristle tufts of which tend to alternately gouge or sweep the material being brushed and to perform these actions irrespective of the direction the brush is being moved.

Still another object of this invention is to provide a brush, the bristle tufts of which readily adapt themselves to irregular surfaces and which perform brushing action with a minimum amount of pressure, thus lengthening the life of the bristles.

And another object of this invention is to provide a brush, the bristle tufts of which are arranged at an acute angle to the body of the brush irrespective of the shape and/or contour of the surface of the brush.

Still even another object of this invention is to provide a brush in which the bristles are mounted as mentioned above and which can be used effectively for cleaning cables or similar members, such as tubing.

To provide brush arrangements which are economical to manufacture, and efficient and reliable in operation, are other objects of this invention.

These and other objects and advantages of this invention will become more apparent from the following specification and single sheet of drawing in which:

FIG. 1 is a bottom plan of one embodiment of the brush;

FIG. 2 is a cross-section taken along line 2—2 of FIG. 1;

FIG. 3 is a fragmentary front elevation of the brush of FIG. 1 illustrating four rows of bristle tufts;

FIG. 4 is a side elevation of a preferred embodiment of the brush comprising this invention;

FIG. 5 is a cross-section taken along line 5—5 of FIG. 4; and

FIG. 6 is a cross-section taken along line 6—6 of FIG. 4.

Referring now to FIGS. 1, 2, and 3 of the drawing, there is illustrated one embodiment of the brush 10. The brush 10 consists of a rectangular shaped body forming a base 13 for mounting a plurality of rows 14, 15, 16, and 17 of bristle tufts 4 thereon. A row of bristle tufts 14, 15, 16, and 17 is constituted by a plurality of tufts lying along a line parallel to the line of the transverse axis of the base 13. Also, it is to be noted that rows 14, 15, 16, and 17 of bristle tufts 4 can be repeated any number of times, depending upon the width of the brush 10 desired. It is to be noted that the body of the brush forming the base 13 can be of other shapes, such as oval, square, triangular, or the like, and that the rows of tufts 14, 15, 16, and 17 can be arranged thereon as described herein.

Each row 14, 15, 16, and 17 of bristle tufts 4 consists of several bristle tufts, preferably three or more as shown.

2

As best seen in FIGS. 2 and 3, the bristle tufts 4 are set in apertures 6 in the body 13 of the brush 10 at acute angles to planes perpendicular to the base, that is, the plane of the base, said planes being parallel to perpendicular planes passing through both the longitudinal and transverse axes of the body of the brush, with these angles being so selected that the bristle tufts 4 will cross each other at substantially the ends thereof.

The acute angle of the bristle tufts 4 and the length of the bristle tufts are so selected that these tufts 4 will cross each other substantially at or near the ends of the bristle tufts. The bristle tufts 4 are arranged at an angle which is acute to planes perpendicular to the base plane, said planes being parallel to perpendicular planes passing through both the longitudinal as well as the transverse axes of the body 13 of the brush 10 so that when the brush is operated or moved on a surface, such as a floor, in the direction of one of these axes, it will cause the rows of bristle tufts 4, pointing in the direction of movement along the axis, to gouge or lift the material being brushed; while the adjacent rows of bristle tufts 4, pointing in the direction opposite to movement of the brush along the axis, will sweep the material being brushed.

As seen best in FIG. 1, the bristle tufts 4 are also arranged on the body 13 of the brush 10 so that they are contiguous with perpendicular planes parallel to a perpendicular plane passing through one of the diagonal axes of the base plane of the base 13; while the same row 14 of the bristle tufts 4 is at an acute angle to perpendicular planes parallel to a perpendicular plane passing through the opposite diagonal axis of the base plane. The bristle tufts of row 15 are arranged on the body 13 of the brush 10 so that they are contiguous with perpendicular planes parallel to a perpendicular plane passing through one of the diagonal axes of the base plane; while the same row 15 of the bristle tufts 4 is at an acute angle to perpendicular planes parallel to a perpendicular plane passing through the opposite diagonal axis of the base plane.

Examination of FIG. 1 of the drawing will show that 40 the planes of contiguity of row 14 and row 15 of the bristle tufts 4 are parallel to a perpendicular plane passing through the diagonal axis A—A'. The bristle tufts 4 in row 14 point in the direction of the intersection of the diagonal axes A—A' and B—B', while the bristle tufts 4 in row 15 point away from the direction of the intersection of the diagonal axes A—A' and B—B'.

Further examination of FIG. 1 of the drawing, will 50 show that the bristle tufts 4 in row 16 and row 17 have planes of contiguity parallel to a perpendicular plane passing through diagonal axis B—B'; and the bristle tufts 4 in row 16 and row 17 are at an acute angle to perpendicular planes parallel to a perpendicular plane passing through the diagonal axis A—A'. The bristle tufts 4 in row 16 point in the direction of the intersection of the diagonal axes A—A' and B—B', and the bristle tufts 4 in row 17 point away from the intersection of the diagonal axes A—A' and B—B'. The next four rows of bristle tufts 4, and succeeding rows of four bristle tufts are arranged in a similar manner. Thus, it can be readily seen that each two rows of bristle tufts 4 are alternately contiguous to or at an acute angle to perpendicular planes parallel to perpendicular planes passing through either of the two diagonal axes of the body 13 of the brush 10.

Row 14 and row 16 of the bristle tufts 4 could be 65 arranged contiguous to perpendicular planes parallel to a perpendicular plane passing through one of the diagonal axes of the base plane, and rows 15 and 17 of the bristle tufts 4 could also be contiguous to perpendicular planes parallel to a perpendicular plane passing through the opposite diagonal axis of the base plane. Thus, every other row of bristle tufts 4 would be alternately contiguous to

or at an acute angle to perpendicular planes passing through either of the two diagonal axes of the base plane of the body 13 of the brush 10.

Referring again to FIG. 1 of the drawing, it is to be noted, for example, that if the brush 10 is moved along a line parallel to the diagonal axis A—A' and in the direction of A, bristle tufts 4 in row 15 will gouge or lift the material being brushed while bristle tufts 4 in row 14 will sweep or push down the material being brushed. If the brush 10 is moved along this line in the direction of A', the bristle tufts 4 in row 14 will gouge or lift the material being brushed and the bristle tufts 4 in row 15 will sweep to push down the material being brushed. If the brush 10 is moved along the line parallel to the diagonal axis B—B', and in the direction of B, the bristle tufts 4 in row 16 will gouge or lift the material being brushed and the bristle tufts 4 in row 17 will sweep or push down the material being brushed. If the brush 10 is moved along this line in the direction of B', the bristle tufts 4 in row 17 will sweep or gouge or lift the material being brushed and the bristle tufts 4 in row 16 will sweep or push down the material being brushed.

Thus, upon operating the brush 10 in the direction of one of the diagonal axes will cause certain bristle tufts 4 to gouge or lift the material being brushed, while the adjacent bristle tufts sweep the material being brushed.

The gouging or lifting action of certain bristle tufts 4 of the brush 10 have an action of such nature that the pressure necessary for brushing a surface is greatly lessened, thereby reducing the tendency toward crinkling and deforming of the bristles. This reduced pressure on the bristles also has the desirable result of greatly lengthening the life of the bristles and the brush 10.

The gouging or lifting action of certain bristle tufts 4 has no damaging effect on the material being brushed due to the fact that adjacent bristle tufts 14 have a counter action of sweeping or pushing down the material lifted.

It is to be particularly noted that the bristle tufts can be arranged at an acute angle to the body 13 of the brush 10 irrespective of the shape and/or contour of the surface thereof. It is also to be noted that the base 13 of the brush 10 can be formed of wood, plastic or metal, while the bristles forming the bristle tufts 4 can be formed of nylon, hair, wire or the like.

Referring now to FIGS. 4, 5, and 6 of the drawing, there is illustrated a preferred embodiment of a brush 11 comprising this invention. This embodiment of the brush 11 can be used effectively to clean cables or tubing used for supporting hanging bridges or the like.

This brush 11 consists of two substantially curved sections 36 and 38 which are arranged to be connected together by a hinge adjusting device 12. Each curved section 36 or 38 has at least two fingers each 32 and 34, respectively, for pivotally connecting one section to the other by a hinge pin 30 which passes through the fingers 32 and 34.

The adjusting device 12 consists of an adjusting screw 28 having a handle 18 at one end for moving the adjusting screw. Suitable block members 50 and 52 are provided on each curved section 36 and 38, respectively, and are attached thereto by screws. These block members 50 and 52 support the adjusting screw 28, as shown. Block member 50 has a cavity 22 provided therein to contain a collar 20 formed on the adjusting screw 28 near the end of the handle 18. The purpose of this collar 20 is to prevent excessive movement of the screw device.

A cavity 54 is also provided in block 52 for receiving a ball 24 having a threaded hole 26 provided therein for receiving the end of the adjusting screw 28 opposite the handle end thereof.

Rows of bristle tufts 40, arranged as previously described, are mounted in apertures in the curved (cylindrical) surfaces of sections 36 and 38.

By moving the screw 28 in the ball socket 24, the sections 36 and 38, including the bristle tufts, can be moved

either toward or away from each other to adjust for the size of the cable, tubing, or railing that is being cleaned. The brush 11 is operated by moving it back and forth and around the curved object being cleaned.

While but two general forms of the invention are shown in the drawing and described in the specification, it is not desired to limit this application for a patent to the particular forms illustrated as it is appreciated that other forms of construction could be made which would use the same principles and come within the scope of the appended claims.

What is claimed is:

1. An arcuate brush arrangement, comprising, an elongated base formed of two substantially quadrant shaped cylindrical sections, each said section of said base having a mating end and a free end, and means for pivotally connecting said sections together at said mating ends to form a continuous semi-cylindrical interior surface for said base, said free ends of said section lying in a common plane and being diametrically opposite from each other, said base having a longitudinal axis extending lengthwise thereof and a transverse axis arranged perpendicular thereto, both of said axes being positioned in said common plane passing through said diametrically and oppositely positioned free end of said sections, a grouping of at least four parallel rows of bristle tufts arranged on said base, each row of bristle tufts consisting of plurality of parallel spaced tufts, said rows of bristle tufts being secured to said interior surface of said sections forming said base at acute angles to planes which are parallel to planes which contain said longitudinal and transverse axes of said base and which are also perpendicular to said common plane containing said longitudinal and transverse axes, said rows of bristle tufts also being arranged so that in said grouping of four rows of bristle tufts, the tufts of an outer row of said four rows of bristle tufts are arranged substantially parallel to a diagonal plane perpendicular to said common plane of said base, with the bristle tufts of the adjacent row of bristle tufts also being parallel to said diagonal plane but extending in the opposite direction, the other two rows of said grouping of four rows of bristle tufts being similarly arranged with respect to a second opposite diagonal plane perpendicular to said common plane of said base, with the ends of said bristle tufts being located in a substantially cylindrical shaped surface, whereby the rows of bristle tufts will alternately gouge and sweep the material being brushed, irrespective of the direction of movement of said brush arrangement.

2. An arcuate brush arrangement, comprising, an elongated base formed of two substantially quadrant shaped cylindrical sections, each said section of said base having a mating end and a free end, means for pivotally connecting said sections together at said mating ends to form a continuous semi-cylindrical interior surface for said base, said free ends of said section lying in a common plane and being diametrically opposite from each other, said base having a longitudinal axis extending lengthwise thereof and a transverse axis arranged perpendicular thereto, both of said axes being positioned in said common plane passing through said diametrically and oppositely positioned free ends of said sections, a grouping of at least four parallel rows of bristle tufts arranged on said base, each row of bristle tufts consisting of a plurality of parallel spaced tufts, said rows of bristle tufts being secured to said interior surface of said sections forming said base at acute angles to planes which are parallel to planes which contain said longitudinal and transverse axes of said base and which are also perpendicular to said common plane containing said longitudinal and transverse axes, said rows of bristle tufts also being arranged so that in said grouping of four rows of bristle tufts, the tufts of an outer row of said four rows of bristle tufts are arranged substantially parallel to a diagonal plane perpendicular to said common plane of said base, with the

bristle tufts of the adjacent row of bristle tufts also being parallel to said diagonal plane but extending in the opposite direction, the other two rows of said grouping of four rows of bristle tufts being similarly arranged with respect to a second opposite diagonal plane perpendicular to said common plane of said base, with the ends of said bristle tufts being located in a substantially cylindrical shaped surface, whereby the rows of bristle tufts will alternately gouge and sweep the material being brushed, irrespective of the direction of movement of said brush arrangement, and means including a ball and socket mech-

anism for adjusting said sections toward as well as away from each other for use in cleaning curved surfaces of various dimensions.
